UNITED STATES PATENT OFFICE.

CHARLES PEARSON, OF CHICAGO, ILLINOIS, ASSIGNOR TO INTERNATIONAL HARVESTER COMPANY, OF CHICAGO, ILLINOIS, A CORPORATION OF NEW JERSEY.

STACKER.

Application filed March 8, 1924. Serial No. 697,727.

To all whom it may concern:

Be it known that I, CHARLES PEARSON, a citizen of the United States, residing at Chicago, in the county of Cook and State 5 of Illinois, have invented certain new and useful Improvements in Stackers, of which the following is a full, clear, and exact specification.

This invention relates to improvements in 10 material handling devices of the type designed to lift and deliver hay or similar materials to an elevated point as in building a stack. It has particularly to do with extensible stackers of the overshot type, and 15 the primary object of the invention is to provide improved mechanism for adjusting and operating the extensible head on the lifting frame so that there will be a wide range of adjustment affording a high lift 20 when required and positive operation of the extensible head without possibility of binding. This principal, and other minor objects, are attained by employment of structure having improved mechanism for controlling the extension and retraction of the 25 stacker head, which structure is characterized by having means for varying the degree of the extension given the sliding arms carrying the stacker head and separate and 30 independent means for positively retracting the arms as the lifting frame and stacker head are lowered.

The invention accordingly resides in the organization and details of construction, or 35 equivalents thereof, hereinafter described and claimed.

Referring to the drawings,—

Fig. 1 is a side view of a stacker embodying the invention showing the lifting frame 40 in its lowered position;

Fig. 2 is a side view of the stacker with the lifting frame elevated and the stacker head extended; and

Fig. 3 is a plan view of the stacker with 45 the stacker head omitted.

The improved stacker comprises a base composed of parallel side sills 10 and 11 connected at their ends by cross pieces 12 and 13 and by an intermediate cross piece 50 14. At one end the base frame has a rigid vertical portion comprising vertical posts 15 which are secured to the side sills and rear cross piece. These posts are connected at the top by a transverse member 16 and 55 are suitably braced as by the diagonally

extending side braces 17 and 18. At points spaced some distance inwardly from the vertical posts 15 there are secured to the inner sides of the side sills short vertical standards 19 on which are pivoted the main 60 lifting arms 20 of the vertically swinging lifting frame. These arms are pivoted on the outer sides of standards 19 and are located directly above the sills, the front ends of which are bevelled off, as at 21, to permit 65 the outer ends of the lifting arms to come close to the ground when the frame is down. Slidable extension arms 22 are mounted on the main lifting arms 20 on which they are guided and held in position by a yoke piece 70 23 secured to the front ends of the arms 20 and by brackets 24 secured to the rear ends of the extension arms 22 and extending below the main arms 20 where they carry anti-friction rollers 25 which travel on the 75 under side of arms 20. These extension arms carry the stacker head 26, which may be of any preferred construction. Secondary lifting or radius arms 27 are pivoted on the base frame at points forward and 80 above the axis of the lifting frame and preferably on the upper ends of the corner posts 15 as shown in Figs. 1 and 2. The secondary arms 27 extend toward the lifting frame, as shown in the drawings, and links 28, 85 each composed of a pair of spaced parallel bars pivoted on opposite sides of the ends of the arms 27 and to the main lifting arms 20 toward their outer ends, as seen in Fig. 1, serve to pivotally connect the main arms 90 20 and secondary lifting arms 27 so that they swing in unison as the lifting frame is raised and lowered. Lifting arms 20 and 27, together with the connecting links 28, 95 provide a construction which becomes locked against further movement when the secondary arms 27 reach a substantially vertical position; that is, further swinging of the lifting frame toward the stack is automatically stopped by the links 28 when the 100 parts reach positions seen in Fig. 2. This construction eliminates the buffer frame heretofore usually employed to limit the upper swing of the lifting frame. The secondary or radius arms 27 control the extension of the slidable arms 22 and for this purpose are connected to the slidable arms by adjustable coupling means comprising sleeves 29 which are movable from 105 point to point along the arms 27 and con- 110

30 nected by flexible elements such as chains 30 to upwardly projecting arms 31, which are preferably formed as extensions on brackets 24 at the lower ends of the sliding 5 arms 22. The secondary arms 27 are provided with means cooperating with sleeves 29 for regulating the degree of extension given the stacker head, consisting in this 10 instance of a series of spaced apertures 32 adapted to register with corresponding apertures in the sleeves 29 which can be held in adjusted position at any point in the length of arms 27 by a pin 33 passed through the registering apertures in the 15 arms and sleeves. In connection with the bars composing the links 28 which connect the main and secondary lifting arms there is provided a spring tension device composed of contractile springs 34 positioned 20 between the arms of links 28 and attached thereto at their upper ends by pivoted staple members 34^a while their opposite ends are attached to short links 35 pivoted on bracket members 36 secured to the main lifting arms 25 20 and extending above the slidible extension arms 22, as clearly shown in Fig. 1, the pivot point of links 35 being just above that of the links 28 to arms 20.

30 The organization comprising the main and secondary lifting arms and the spring cushion means cooperating therewith, which has just been described, does not form the subject matter of the present application but is described and claimed in a copending 35 application, Serial No. 639,243, filed May 16, 1923.

40 As means for applying power to raise and lower the lifting frame, there is provided a vertically swinging jib composed of upwardly converging beams 37 which are pivoted on the side sills to their lower ends and rigidly connected together at their upper ends. The jib has its outer end connected to the ends of the main lifting arms 45 20 by means of lifting rods 38 which are pivoted to the end of the jib members 37 and to the outer ends of the lifting arms 20. Between the outer ends of the jib members 37 there is journaled a sheave 39, and twin 50 sheaves 40 are journaled centrally of the transverse bar 16 in alignment therewith and with another sheave 41 journaled in the swiveled bracket on the base of the frame. An operating cable 42 passes over 55 the several sheaves and is attached to the jib, extending then to the source of power in the usual manner. The construction so far described provides for raising and lowering the lifting frame and for variable 60 extension of the stacker head, if desired, but it has been found in practice that the weight of the stacker head and extension arms alone cannot be depended upon to cause falling back or retraction of the extension arms 22 when the lifting frame is

being lowered, and, in order to provide positive means for retracting the extensible sliding arms 22 during the lowering of the lifting frame, there are provided fixed brackets 43 each consisting preferably of a pair of 70 upwardly and inwardly inclined converging bars connected at their outer ends and secured to the vertical portion and braces of the base frame near the upper ends of the corner posts 15. These brackets 43 provide 75 properly located points of attachment for flexible retracting connections, such as the lengths of chain 44, which connect the brackets 43 with the upper ends of the arms 31 on the slidible extension arms 22. 80

The relative positions of the points of attachment of chains 44 to brackets 43 and to arms 31 are such that these two points approach each other as the lifting frame rises, and draw apart as the frame is 85 lowered, the chain length and relation of attaching points being such as to compel return of the extension arms to their extreme retracted position, if they have been given any extension during the raising of 90 the lifting frame.

The operation of the stacker is effected through the cable 42 in well known manner, the improved construction above described 95 functioning as follows:

When the lifting frame is in lowered position, as in Fig. 1, the relation of parts is such that springs 34 are under tension and exert a lifting action on arms 20. If cable 42 is now pulled, the jib 37 will begin its swinging, and lifting rods 38 will pull on lifting arms 20, the assistance of springs 34 causing the lifting movement to start without straining and with application of less power than heretofore required in similar structures. As lifting progresses, it will be obvious that the springs 34 will become slack during an intermediate period in the lifting operation, and, as the main and secondary arms continue to rise, the links 28 connecting them swing in such a way that the upper ends of springs 34 are shifted from one side of their points of connection to arms 20 to the other side thereof, and, as the end of the raising movement is reached, the springs are again placed under tension, as in Fig. 2, and the end of the upward swing is also cushioned, the tension of the springs then acting to cause recoil of the lifting frame, thereby initiating the downward swing thereof. During the lifting and lowering operation just referred to, it was assumed that sleeves 29 were pinned in the apertures nearest the pivots of arms 27. Under those conditions, there was no extension of arms 22 and no additional lift given the stacker head as chains 30 remain slack. When it is desired to increase the height of the lift, the sleeves 29 are pinned, usually by successive stages, in the several apertures 115 120 125 130

32 of the arms 27 to follow the rising stack, and, for purposes of illustration, the sleeves 29 have been illustrated as fixed in the second apertures from the ends of the arms 5 27 thus getting the next to highest possible lift. Under these conditions swinging of the arms 27 in unison with the lifting frame but on differently positioned axes will cause the chains 30 to become taut after the lift 10 has progressed a certain distance, and extension of arms 22 will then continue until the lifting frame has reached the position shown in Fig. 2, the pull back chains 44 in the meantime becoming more and more 15 slack. Upon return movement, if the extension arms 22 stick or bind and fail to move down on the arms 20 of their own weight, the chains 44, which soon will become taut, will exert a pull on the lower ends of these arms 20 and positively force their return to the initial retracted position. It will be evident that the degree of extension given the arms 22 will be governed by adjustment of sleeves 29 on the arms 27 and that the extension 25 given will become greater as the sleeves are pinned in the apertures farthest from the pivot of the arms 27.

The above description will make it clear that a simple, strong and easily operated 30 construction has been devised in which the height of lift can be quickly and easily adjusted within a considerable range and that both the extension and retraction of the stacker head are positively governed, efficient 35 operation being, therefore, made certain. While the preferred form of the novel construction constituting the invention has been described, it will be understood that considerable variation is possible without departing from the scope of the invention 40 as defined in the following claims.

What is claimed as new is:

1. The combination of a normally stationary base frame, a lifting frame pivoted 45 thereon, said frame comprising a main lifting arm and an extension arm, means for swinging the lifting frame upwardly and for simultaneously causing projection of the extension arm, and means independent of 50 said swinging means and having one end connected to means fixed relative to the base frame for effecting retraction of the extension arm on downward movement.

2. The combination of a base frame, a 55 lifting frame pivoted thereon, said frame comprising a main lifting arm and an extension arm, means for swinging the lifting frame, a secondary lifting arm pivoted on the base frame on an axis above that of the 60 lifting frame, means causing the lifting frame and secondary arm to swing in unison, means actuated through upward movement of the secondary arm for causing projection of the extension arm, and independent 65 means for effecting retraction of the exten-

sion arm on downward movement of the lifting frame.

3. The combination of a base frame, a lifting frame pivoted thereon, said frame comprising a main lifting arm and an extension arm, means for swinging the lifting frame, a secondary lifting arm pivoted on the base frame on an axis above that of the lifting frame, means causing the lifting frame and secondary arm to swing in unison, 70 means actuated through upward movement of the secondary arm for causing projection of the extension arm, and independent means, comprising a flexible connection between the extension arm and a fixed point 75 of attachment on base frame, for effecting retraction of the extension arm on downward movement of the lifting frame.

4. The combination of a base frame, a lifting frame pivoted thereon, said frame comprising a main lifting arm and an extension arm, means for swinging the lifting frame, a secondary lifting arm pivoted on the base frame forwardly of the lifting frame on an axis parallel with and above 80 the axis of said frame, a link pivotally connecting the main lifting arm to the secondary arm, a flexible element connecting the lower end of the extension arm to the secondary arm, and a second flexible element connecting the lower end of the extension arm with a fixed point of attachment adjacent 85 the pivot of the secondary arm.

5. The combination of a base frame, a lifting frame pivoted thereon, said frame comprising a main lifting arm and a slide- 90 able extension arm, means for swinging the lifting frame, a secondary lifting arm pivoted on the base frame forwardly of the lifting frame, and flexible connections between the lower portion of the extension arm and the secondary arm and between the extension arm and a forward point of attachment on the base frame.

6. The combination of a base frame, a lifting frame pivoted thereon, said frame comprising a main lifting arm and a slide- 100 able extension arm, means for swinging the lifting frame, a secondary lifting arm pivoted on the base frame forwardly of the lifting frame, a flexible connection between the lower portion of the extension arm and the secondary arm including a member adjustable from point to point along said arm, and a second flexible connection between the extension arm and a forward point of attachment on the base frame.

7. A hay stacker including a normally stationary base frame, a hay lifting frame upon the outer end of which hay may be deposited, said lifting frame including a main lifting arm and an extension arm movable pivotally with the main arm and longitudinally slideable relative thereto, means for swinging the lifting frame upwardly, a de- 115 120 125 130

vice for causing projection of the extension arm, and means independent of said swinging means and having one end anchored at a point which is fixed relative to said base frame for effecting retraction of the extension arm on downward movement thereof.

8. A hay stacker comprising a base, a lifting frame, an extension arm, the lifting frame being swingable from a loading position to an unloading position, means for swinging said lifting frame, and lost motion connecting means independent of said swinging means for effecting retraction of the extension arm on downward movement of the lifting frame to loading position, said lost motion means having one end anchored

to said extension arm and its other end anchored at a point which is fixed relative to said base frame.

9. A hay stacker comprising a base frame, 20 a lifting frame pivoted thereon, said frame comprising a main lifting arm and an extension arm, means for swinging the lifting frame upwardly, means for causing the projection of the lifting arm, and a device independent of said swinging means and wholly operatively interposed between said base frame and said extension arm for effecting retraction of the extension arm as the lifting frame moves downwardly. 25

In testimony whereof I affix my signature. 30

CHARLES PEARSON.
